UNITED STATES PATENT OFFICE.

CECIL F. ADAMSON, OF EAST PALESTINE, OHIO.

DESIGN FOR A PORTABLE VULCANIZER.

42,721.

Specification for Design.

Patented July 9, 1912.

Application filed April 4, 1912. Serial No. 688,552. Term of patent 14 years.

To all whom it may concern:

Be it known that I, CECIL F. ADAMSON, a citizen of the United States, residing at East Palestine, in the county of Columbiana and State of Ohio, have invented a new, original, and ornamental Design for Portable Vulcanizers, of which the following is a specification, reference being had to the accompanying drawing, forming part thereof.

The figure is a perspective view of a portable vulcanizer showing my new design.

I claim:

The ornamental design for a portable vulcanizer as shown.

CECIL F. ADAMSON.

Witnesses:

EVERETT L. LYON,
CLARA L. MORROW.
